UNITED STATES PATENT OFFICE.

PETER J. GROSS, OF BROOKLYN, NEW YORK, ASSIGNOR OF ONE-HALF TO
HERMAN OST AND FRANK P. WILDEROTER, OF SAME PLACE.

DESIGN FOR A BOTTLE-STOPPER LEVER.

SPECIFICATION forming part of Design No. 27,860, dated November 16, 1897.

Application filed August 16, 1897. Serial No. 648,475. Term of patent 14 years.

To all whom it may concern:

Be it known that I, PETER J. GROSS, a subject of the Emperor of Germany, residing at Brooklyn, county of Kings, and State of New York, have invented and produced a new and original Design for a Bottle-Stopper Lever, of which the following is a specification.

My invention relates to levers, bails, and the like employed in bottle-stoppers; and it consists in the configuration of one of the levers employed in such structures.

In the drawings forming part of this specification, Figure 1 is a perspective view of the lever, and Fig. 2 is a front elevation.

The lever comprises a piece of metal, as wire, bent or otherwise conformed into a yoke shape, having the vertically-disposed side pieces 1 and circular top cross-piece 2.

At the free ends the lever is curved outwardly, as at 3, and then reversely curved in-

wardly, as at 4, to form the reverse-curved eye 5, the eye lying in the same vertical plane as the inwardly-curved portion 3, the end of the wire at the eye being offset at right angles to the plane of the side pieces 1, as shown at 6, the ends or extensions 6 thus formed extending inwardly toward each other and away from the side pieces 1, as clearly indicated in Fig. 2.

Having described my invention, I claim—
The design for a bottle-stopper lever, or the like, substantially as herein shown and described.

Signed at the city, county, and State of New York this 11th day of August, 1897.

PETER J. GROSS.

Witnesses:

JOSEPH L. LEVY,
B. S. WISE.
